UNITED STATES PATENT OFFICE

134,180

DESIGN FOR A HOIST

Humphrey F. Parker, Kenmore, N. Y., assignor to
Columbus McKinnon Chain Corporation, Ton-
awanda, N. Y.

Application May 12, 1942, Serial No. 106,873

Term of patent 14 years

To all whom it may concern:

Be it known that I, Humphrey F. Parker, a citizen of the United States, residing at Kenmore, in the county of Erie and State of New York, have invented a new, original, and ornamental Design for Hoists, of which the following is a specification, reference being had to the accompanying drawing, forming part thereof.

Fig. 1 is a side elevational view of a hoist, showing my new design;

Fig. 2 is a top plan view thereof;

Fig. 3 is a front end elevational view thereof with the control box and hoist block omitted for convenience of illustration, and;

Fig. 4 is a rear end elevational view thereof with said members omitted for the same reason.

The dominant features of the design reside in the portions shown in full lines.

This application is a continuation in part of application Serial No. D-105,459 filed January 27, 1942, now abandoned.

I claim:

The ornamental design for a hoist, as shown and described.

HUMPHREY F. PARKER.
